CLAIM

The ornamental design for a bait holder, as shown and described.

DESCRIPTION

FIG. 1 is an upper perspective view of a bait holder showing my new design.

FIG. 2 is a front view of a bait holder showing my new design.

FIG. 3 is a side view of a bait holder showing my new design.

FIG. 4 is a rear view of a bait holder showing my new design.

FIG. 5 is a top view of a bait holder showing my new design; and,

FIG. 6 is a bottom view of a bait holder showing my new design.

Any shading and cross-hatching are not features of the design but are utilized to illustrate the surface contours of the bait holder in the drawings.

1 Claim, 6 Drawing Sheets
